UNITED STATES PATENT OFFICE.

JOHN J. DUNN, OF ROCHESTER, NEW YORK, ASSIGNOR OF ONE-HALF TO ORLANDO M. FASANO, OF ROCHESTER, NEW YORK.

COLLAR-BAND.

1,367,737.

Specification of Letters Patent.

Patented Feb. 8, 1921.

Application filed April 7, 1920. Serial No. 372,094.

To all whom it may concern:

Be it known that I, JOHN J. DUNN, a citizen of the United States, residing at Rochester, in the county of Monroe and State of New York, have invented certain new and useful Improvements in Collar-Bands, of which the following is a specification.

The object of this invention is to provide 10 a new and improved form of a collar band for a shirt.

This and other objects will be fully illustrated in the drawings, described in the specification and pointed out in the claim 15 at the end thereof.

In the drawings,

Figure 1 is a perspective view of a shirt front and collar band containing my improvement.

Fig. 2 is a detail view of a portion of the collar band containing my improvement.

In the drawings, like reference numerals indicate like parts.

In the drawings, reference numeral 1 indicates a shirt that buttons in front and has the collar band 2 thereon. This collar band is preferably made of two or more layers of material, which layers are stitched together, preferably along the bottom edge 25 thereof. At 3 the front layer is provided with a buttonhole therethrough, which hole does not go through the back layers of the collar band. The band is not stitched along the edge around the buttonhole but is 30 stitched back of or above the button hole instead so that at the edge around this buttonhole the layers are left unstitched for a short distance and the layers can be separated to permit the insertion of a collar 35 button between the layers. In this way, a small pocket is formed in the collar band which has the buttonhole in the front thereof and is closed at the back. When the collar button is inserted in the buttonhole, the 40 base of the collar button rests against the 45

rear layer of the collar band and does not come into contact with the neck of the person who wears the shirt.

It is a well known fact that shirts are heavily starched in the laundry so that the 50 loose layers of the material thereof are fastened more or less firmly together by the ironing and it is frequently difficult to separate them. To avoid this difficulty and make it easier to separate the layers of the 55 material at the buttonholes, I provide an extension 4 integral with the outer layer. When the shirt is laundered and ironed, this extension will slightly overlap the bosom of the shirt and can be easily raised therefrom, 60 and when it is once separated it can be used as a handle to pull apart the layers of the collar band so as to expose the buttonhole which goes through the outer layer only and makes the buttonhole accessible from both 65 the front and the rear. This operation is done without disturbing the rest of the shirt or interfering with its finish.

The extension 4 is small and so placed that it will be easily ironed down and will 70 not be torn in the ironing and is yet available for the opening of the buttonhole when needed as above described.

I claim:

A collar band for a shirt, said band having 75 two layers of material therein sewed together along one edge, a button hole through one of said layers, an extension to the said layer below the hole, said extension extending below the band, the said layers being 80 left unsewed between the extension and the hole but being sewed together above and at one side of the hole leaving a pocket therein between the layers that opens at the bottom and on the adjacent side, said pocket being 85 closed on the other two sides, said extension overlapping the upper edge of the shirt bosom.

In testimony whereof I affix my signature.
JOHN J. DUNN.
